UNITED STATES PATENT OFFICE.

DONALD ELIJAH PLYMPTON, OF ELLWOOD CITY, PENNSYLVANIA.

BLANK TRANSFER MECHANISM FOR BRICK PRESSES.

Application filed December 8, 1922. Serial No. 605,609.

To all whom it may concern:

Be it known that I, DONALD E. PLYMPTON, a citizen of the United States, residing at Ellwood City, in the county of Lawrence 5 and State of Pennsylvania, have invented new and useful Improvements in Blank Transfer Mechanism for Brick Presses, of which the following is a specification.

The object of the invention is to provide 10 a mechanism, more especially designed for use as a feeder for brick presses and similar machines whereby objects or blanks and particularly those of a substantially uniform size and shape and of more or less soft or 15 plastic properties may be picked up and removed from one station and transferred to another, or for example, may be removed from a continuously traveling belt or conveyor such as that by which molded brick 20 blanks are conducted from the molding mechanism, and carrying said blanks without distortion to and depositing the same in a brick press; and incidentally it is a further and important object of the invention 25 to provide a transfer mechanism where- in a carrier when loaded and while traversing the path provided therefor between the receiving station and the delivery station shall move and particularly shall start at 30 the receiving station and stop at the delivery station under such conditions as to avoid jarring and thereby distorting the blank without consuming an unnecessary amount of time.

35 A further object of the invention is to provide a transfer mechanism which while intended to operate in accurately timed relation with the brick press or any equivalent apparatus at the delivery end of the path of 40 movement of the carrier, shall be capable of receiving and engaging blanks or other objects which may be presented irregularly or at irregular intervals at the receiving station.

45 With the foregoing and further related objects in view the invention consists in a construction, combination and relation of agencies of which a typical embodiment is 50 illustrated in the accompanying drawings, wherein,

55 Figure 1 is a side view of the transfer apparatus associated with receiving and delivery stations which in this instance are represented by a conveyor belt and the outline of a conventional form of brick press.

Figure 2 is a plan view of the apparatus

with the power driven return devices omitted.

Figure 3 is a side view on a scale enlarged as compared with Figure 1 and partly in 60 longitudinal section, with the carriage in the position which it occupies just before it reaches the delivery station.

Figure 4 is an end view of the apparatus viewed from the position of the delivery 65 station.

Figure 5 is a view of the opposite or receiving station end of the same.

Figure 6 is a detail view of the means for setting the blank clamps preparatory to 70 engagement with an object at the receiving station.

Figure 7 is a view similar to Figure 6 at an intermediate point in the setting movement of the clamps.

75 Figure 8 is a view similar to Figures 6 and 7 showing the parts in the positions which they occupy when the setting of the clamps has been completed.

Figure 9 is a detail view of the final blank 80 actuated trip.

Figure 10 is a similar view of the preliminary blank actuated trip.

Figures 11 and 12 are detail views showing respectively the normal and delivery 85 positions of the jaw of one of the slide clamp members.

Figure 13 is an enlarged detail plan section on the line 13—13 of Figure 3.

The mechanism contemplates essentially a 90 reciprocating carrier 20 with which is connected an oscillatory pendulous actuator 21 mounted for swinging movement from an axis represented by the shaft 22 through a path extending in both directions from the 95 vertical plane of said axis, clamping devices supported by the carrier, means for causing the closing and opening of the clamping devices at opposite ends of the path of movement of the carrier, and power 100 driven means for effecting the return movement of the actuator as the carrier moves from the delivery station represented in this instance by the brick press 23 to the receiving station represented in this instance by 105 the conveyor belt 24. In the illustrated embodiment of the invention the actuator consists of a heavy ratchet wheel 25 fixed to the shaft 22 which also carries a pulley or sprocket 26 adapted to receive motion from a power chain or belt 27 to the end that a 110 continuous rotary motion is communicated

continuous rotary motion is communicated

to the ratchet; together with a dog 28 mounted upon the actuator which consists of a heavily weighted pendulum and is yieldingly held by a spring 29 in position for engagement with a tooth of said ratchet. Carried by the dog through arms 30 projecting therefrom are rolls 31 adapted at the limit of the return movement of the carrier to engage release cams 32 projecting 10 from the side standards 33 of a suitable supporting frame upon which the shaft and its attachments are mounted. For maintaining the dog in its ratchet releasing position during the forward, active or transferring 15 movement of the carrier which is connected with the actuator by means of rods 34, there is employed a pawl 35 arranged to engage a lug 36 projecting from the dog 28 through a slot 37 in the face of the actuator. Said 20 pawl is provided with a trip rod 38 extending longitudinally of the actuator through a suitable guide 39.

The carrier traverses a track 40 of substantially U-form in plan with its closed 25 end located adjacent to the receiving station and having its arms supported by brackets 41 projecting from the standards 33, and the front and rear rollers 42 and 43 of the carrier are arranged at different 30 gages so as to traverse different paths on the tracks, with depressions 44 and 45 formed in the tracks adjacent to the receiving station to permit of the slight depression of the carrier when it reaches the position for 35 receiving a load, and to the end that a slight forward movement of the carrier from its initial loading position will be accompanied by a slight elevation of the carrier for a purpose which will appear hereinafter. 40

Arbitrarily assuming, for convenience, that the forward end of the carrier is that end which is in advance during the movement of the carrier from the receiving toward the delivery end of its path or during 45 the period that the carrier is loaded, the blank or object engaging means with which the carrier is provided may be described as consisting of clamps each having a rear swinging member 46 and a front sliding member 47 or a rear passive member adapted to be withdrawn during the rearward or return movement of the carrier so as to pass over any blanks or objects which may be located 50 on the conveyor belt 24, as shown in full lines in Figure 1, and a front active member which is adapted to be moved toward and from the rear passive member to a greater or lesser extent necessary to secure 55 effective clamping action of the blank or object therebetween. In the construction illustrated a plurality of clamps is illustrated and the rear members thereof are preferably connected for simultaneously 60 movement to form a yoke 48, see Figure 5,

upon which are mounted rotary disks constituting jaws for contact with the blanks at their rear ends. The arms of the yoke are mounted upon pivots 49 on the carriage and to one of said arms is attached a folding spring 50 designed to cause a folding or retracting action of the rear or passive jaws when the latter are released,—said jaws being normally held in their operative position by means of a latch 51 which is herein shown as pivoted at 52 to the under side of the carriage and is yieldingly held in engaging relation with an arm of the yoke by means of a spring 53. 70

The front or active members of the clamps are mounted to slide upon and in a path parallel with that of the carrier by means of horizontal arms 54 fitted in dove-tailed guides 55 and provided with actuating springs 56 connected at their rear ends with bell crank tensioning levers 57 which carry between them a terminal roller 58 for engagement with a stationary cam 59. 80

Associated with the active jaws of the clamps are setting levers 60 and 61 fulcrumed upon the carriage at 62 in co-axial relation and connected by links 63 with the active jaws so that the depression of the free ends of said setting levers will serve to force the said jaws forwardly in opposition to the tension of the springs 56. The setting lever 61 is provided with an extension 64 provided with a terminal arm 65 arranged in overlapping or overlying relation with the setting lever 60 so that the setting of both 90 levers may be accomplished by the depression on the free end of the lever 61. 95

In operative relation with each of the setting levers there is arranged the brick-actuated trip of swinging or pendulous form 100 consisting in the construction illustrated of a tube 66 pivotally mounted near its upper end as indicated at 67 and having a beveled lug 68 adapted to extend over the setting lever with which it is related to hold the 110 lever in its depressed position. 105

Depression of the setting lever obviously 115 will cause the swinging movement of the trip sufficient to permit engagement with the lug thereof by reason of the beveled surface of the latter as clearly shown in Figures 9 and 10. In addition to the tubular member 66 each trip embodies a stem 69 slidably fitted in the bore of the tubular member and provided at its lower end with a ball 70 with which the bricks, blanks or other objects carried by the conveyor belt may contact with the minimum risk of marking or scoring the blank, and the trips are mounted in such a relation to the direction of movement of the blanks as carried by the belt at the receiving station tends to be swung in the direction indicated by the dotted lines in Figure 10 so as to disengage the lug of the trip 120 from the setting lever and thereby release 125

the lever to permit the movement of the connected clamp member into engaging relation with a blank arranged in the path thereof. The upper end of the stem 69 of the brick actuated trip is provided with a head 71 to serve as a stop to limit the downward movements of the ball, and also with a trip arm 72 which it terminally arranged in the path of the setting lever, so that when the latter is released by the swinging movement of the brick actuated trip and the consequent withdrawal of the lug 68 from engagement therewith, the upward movement of the setting lever brings it into contact with the trip arms 72 and thus raises the stem 69 with the ball at the lower extremity thereof out of the path of the brick.

The setting lever 61 which as above described is utilized as a means of causing the setting movements of both levers by reason of the overlapping relation of its arm 65 with the setting lever 60, is depressed terminally to extend the forward or active clamp jaws during the return movement of the carrier by the contact of a roller 73 on the free end of the lever 61 with a depressing cam 74 which is supported by one of the standards 33 of the frame, and to the end that the said roller may pass this cam on its forward or loaded movement without interference, the roller is provided with a spindle 75 affording a lateral movement of the roller with relation to the setting lever, and coiled upon said spindle is a spring 76 serving to normally hold the latter in its position to engage the cam 74. Adjacent to the cam 74 however, there is disposed a laterally operative cam 77 which imparts lateral movement to the roller 73 in opposition to the actuated spring 76 during said forward or loaded movement of the carrier.

When the carrier reaches its receiving station it is secured by locking means pending the proper engagement of the clamps with the blanks as they are presented by the conveyor belt and which may be presented with some irregularity due to the operation of the molding mechanism which forms no part of the present invention, and in the construction illustrated, see Figure 3, these locking means consist of latches 78 and 79 for respective engagement with the catches 80 and 81 arranged in a slightly spaced relation or with catch 81 slightly in advance of catch 80, and the tails of the latches indicated at 82 are arranged in the paths of the setting levers so that as the setting levers are released through the displacement of the blank actuated trips 66, they successively trip the latches 78 and 79.

The discharge of the blanks which have been brought forward from the receiving station to the delivery station, to the end that such discharge may be effected in timed relation with the operation of the brick

press having for example, a slide 83 connected for example by means of a rod 84 or its equivalent with a rocker 85 actuated by a cam 86, is effected by means of a trip finger 87 which on the advance of the slide 83 to 70 receive a new charge of blanks comes into contact with and trips the latch 51 which holds the rear or passive clamp members in their operative position, and thus by the rearward swinging movement of said jaws 75 disengages the blanks and permits their deposit upon the slide 83.

The blanks, shown in dotted lines in Figure 2 are rectangular in cross section and have previously been severed from a ribbon 80 of plastic brick material which has been extruded through a die in any common or preferred manner. The frictional action of the walls of the die on the brick material produces minute cracks on the outer faces of 85 the ribbon, but such cracks are not formed on the vertical faces of the blanks as they are presented to the present machine, for the reason that these vertical walls are formed by the severing of the blanks from the ribbon of brick material. Now as the top and bottom faces of each blank are the faces which have the minute cracks or fissures, I propose to turn the blank through an angle of 90° when passing from the receiving station to the delivery station in order that the blank may be fed into the brick press with the cracked faces of the blank in a substantially vertical position, whereby the action of the plunger of the press coming down on the 90 top of the blank will close the cracks rather than open the same as would occur if the cracked surfaces of the blank were at the top and bottom when subjected to the action of the plunger.

In order to accomplish this turning of the blanks the rear or passive clamp members are provided with rotary disk-like jaws 88 and the front or active clamp members with rotary jaws 89 which are preferably 110 pivoted as at 90 upon spindles 91 having attached crank arms 92 and 93 connected by a rod 94, and with the crank 93 provided with an additional arm 95 connected by rod 96 with an arm 97 carried by the forward end 115 of one end of the connecting rods 34, as plainly shown in Figures 1 and 2. As the carrier moves forward from its receiving to its delivery position, due to the swinging movement of the actuator 21, a rocking movement is imparted to the connecting rod 34 which causes an elevation of the arm 97 and hence a turning movement of the spindles 91 together with the jaws 89 carried thereby. The rotary mounting of the jaws 120 88 permits of a corresponding rotation thereof so that whereas the blank when engaged by the jaws at the receiving station may be in an upright or edgewise position, it is turned during the advance movement of 125

130 it is turned during the advance movement of

the carrier through an angle of 90° to bring the cracked surfaces of the blank into upright positions for discharge of the blank at the delivery station. The pivotal connection of the jaws 89 with the spindles 91 permits the swinging movement of the former during the discharge of the blank, and this movement of the jaw 89 is complementary to the receding movement of the co-operating rear jaw 88 which in receding, under the tension of the actuating spring 50, comes into contact with the lower end of the trip rod 38, Figure 1, and thereby disengages the pawl 35 from the dog 28 and permits engagement of the latter with the ratchet so that the rotary movement of the latter in the direction indicated by the arrow thereon may be utilized to return the carriage to its initial or receiving position.

As the carriage approaches its receiving position the rear or passive jaw of each clamp is engaged by a cam 98 and swung in opposition to the spring 50, as shown progressively by Figures 6, 7 and 8 to its operative position where it is again secured by means of the latch 51. The carrier on reaching its receiving position, as hereinbefore explained, is depressed by reason of the dropping of its bearing rollers into the depressions 44 and 45 of the track, the engagement of latches 78 and 79 with the catches 80 and 81, and the disengagement of the dog 28 from the power driven ratchet 25 by which the carrier has been returned; and during said return movement as also hereinabove explained the active jaws of the clamps or those which are mounted on the carriage for sliding movement and which are capable of the variable movement determinable for the size of the object such as the brick or blank interposed between the same and the passive jaws of the clamps, are set by the depression of the free end of the setting lever 61 through the action of the roller 73 upon the cam 74.

Assuming that the conveyor belt 24 is continuously movable but presents the blanks with more or less irregularity or spacing to the transfer mechanism, and that the carrier of the latter has been positioned as above explained at the receiving station, the first blank which approaches the mechanism comes in contact with the blank actuated trip 66 which controls the setting lever 60 and which trip for convenience may be termed the preliminary trip for the reason that it is necessary for the blank to pass this trip without materially disturbing the mechanism, in order that it may pass onward to the second or main trip. Owing to the fact that the second or main trip serves to lock the setting lever 61 in its jaw opening position and said lever 61 serves to hold the lever 60 in its set position by reason of the arm 65, the first blank will pass

under the preliminary trip 66 as indicated in Figure 10 and by reason of a supplemental cam arm 99 operating in connection with a guide roller 100 the stem carrying the ball 70 of said trip will be elevated to 70 permit passage of the blank without mutilating or marring the same and said blank will hence move forward until it comes into contact with the ball 70 of the second or main trip 66. Pressure of the blank against 75 this trip will deflect it sufficiently to release the setting lever 61 which in turn will release the connected clamp jaw and permit the clamping of the blank between the jaw 48 connected with said released setting lever 80 and the complementary passive jaw 89 at the rear end of the carrier. Furthermore the release of the setting lever 61 and its consequent upward movement will cause the tripping of the latch 78 and its disengagement with the catch 80 so that the carrier will receive a forward impulse due to the weight of the pendulous actuator 21. This forward movement will be arrested by the engagement of the latch 79 with the catch 90 81 after the carrier has moved a distance of say one-half an inch, and such forward movement has accomplished, by reason of the depressions 44 and 45 of the tracks an upward movement of the carrier sufficient to 95 raise the engaged blank out of contact with the belt. The second brick or blank to approach the apparatus, either in close succession or in intervals depending upon the rapidity with which the blanks are carried by the belt, will again engage the preliminary blank actuated trip which in the mean time has dropped back to its initial position and has resumed its engagement with the setting lever 60 to thereby hold the second 100 clamp in its open position. Upon the engagement of said trip by the second brick however, and its upward swinging movement due to the progress of the brick, it releases the setting lever 60 which in turn 105 swings upward to permit the closing of the second clamp and the consequent engagement of the brick or blank thereby, and the incidental disengagement of the latch 79 from the catch 81, whereupon the carrier resumes its interrupted forward movement under the influence of the actuator. As hereinbefore explained the pressure roller 73 of the setting lever 61 is deflected by the cam 77 as it passes the latter, and when the rollers 58 of the tensioning lever comes into contact with the cam 59 it serves to retard the forward movement of the carrier until, when said roller engages the seat 101 in said cam, the carrier is brought to rest without jar or shock and is thus held ready for the action of the press operating trip 87 which will release and permit the deposit of the blanks upon the slide of the press.

The mounting of the pendulous actuator 120

- to swing through its neutral position on the vertical plane of its axis of suspension is designed to afford a relatively rapid movement of the carrier during the greater portion of its progress between its receiving station and the delivery station but to cause a gradual or relatively slow starting movement of the carrier when released at the receiving station and the gradual reduction 5 in the speed of movement of the carrier as it approaches the delivery station, and while in practice it is preferred to arrange the greater proportion of the path of the actuator on that side of its neutral plane which 10 is toward the receiving station, so as to utilize to a greater extent the gravitational action of the actuator in the forward movement of the carrier, and while it is also found desirable under some conditions to supplement 15 this forward movement of the actuator by means of a spring 102, as indicated in the drawing, so that there may be no lagging of the mechanism in leaving the receiving station upon release of the second latch, it is 20 found that the tendency of the actuator to lag during its forward movement after it passes the neutral plane particularly when 25 supplemented by the cushioning effect of the contact of the roller 58 with the cam 59, 30 serves to bring the carriage to a rest at the delivery station without such jar or shock as can effect the form of the blank or object supported by the carrier. In this connection it should be noted that the release of the active 35 jaws of the clamps has reduced the tension upon the clamp actuating springs 56 which are connected with the tensioning lever 57, but the engagement of the roller 58 with the cam 59 serves to increase the tension 40 of said springs as the carriage approaches the limit of its movement, so as to produce a substantial cushioning effect.

What is claimed is:

1. A transfer apparatus for blanks and other objects having an oscillatory carrier mounted for forward and return movements between a receiving or loading station and a delivery station and gravitally movable in the forward direction, means for returning the carrier, and carrier supported blank holding means for engaging and releasing the same respectively at said stations.
2. A transfer apparatus for blanks and other objects having an oscillatory carrier mounted for forward and return movements between a receiving or loading station and a delivery station and gravitally movable in the forward direction, means for returning the carrier, and carrier supported blank holding means for compressively engaging and expansively releasing the same respectively at said stations.
3. A transfer apparatus for blanks and other objects having an oscillatory carrier mounted for forward and return movements between a receiving or loading station and a delivery station and gravitally movable in the forward direction, means for returning the carrier, and carrier supported blank holding means for engaging and lifting the same at the receiving station and releasing them at the delivery station.
4. A transfer apparatus for blanks and other objects having an oscillatory carrier mounted for forward and return movements between a receiving or loading station and a delivery station and gravitally movable in the forward direction, means for returning the carrier, and carrier supported blank holding means for engaging and lifting the same at the receiving station and releasing them at the delivery station.
5. A transfer apparatus for blanks and other objects having a carrier mounted for forward and return movements between a receiving or loading station and a delivery station and gravitally movable in the forward direction, means for returning the carrier, and carrier supported blank holding means for successively engaging, turning the blank on a horizontal axis and releasing the same.
6. A transfer apparatus for blanks and other objects having a carrier mounted for forward and return movements between a receiving or loading station and a delivery station and gravitally movable in the forward direction, means for returning the carrier, and carrier supported blank holding means for successively engaging, lifting, turning the blank on a horizontal axis and releasing the same.
7. A transfer apparatus for blanks and other objects having an oscillatory carrier mounted for forward and return movements between a receiving or loading station and a delivery station and gravitally movable in the forward direction, locking means for retaining the carrier at the receiving station, means for returning the carrier from the delivery to the receiving station, carrier supported blank holding means for engaging and releasing the same respectively at said stations, and blank actuatable means for releasing the carrier for forward movement.
8. A transfer apparatus for blanks and other objects having a carrier mounted for forward and return movements between a receiving or loading station and a delivery station and gravitally movable in the forward direction, locking means for retaining the carrier at the receiving station, means for returning the carrier from the delivery to the receiving station, carrier supported blank holding means for engaging and releasing the same respectively at said stations, and blank actuatable means for releasing the carrier for forward movement, retarding means being provided to cushion the approach of the carrier to the delivery station.
9. A transfer apparatus for blanks and

other objects having a carrier mounted for forward and return movements between a receiving or loading station and a delivery station and gravitally movable in the forward direction, means for returning the carrier, and carrier supported blank holding means for engaging and releasing the same respectively at said stations, and retarding means having a progressively tensionable element to cushion the approach of the carrier to the delivery station.

10. A transfer apparatus for blanks and other objects having a carrier mounted for forward and return movements between a receiving or loading station and a delivery station and gravitally movable in the forward direction, means for returning the carrier, and carrier supported blank holding means for engaging and releasing the same respectively at said stations, retarding means consisting of a spring pressed roller and a coacting cam surface to cushion the approach of the carrier to the delivery station.

15. 11. A transfer apparatus for blanks and other objects having a carrier mounted for forward and return movements between a receiving or loading station and a delivery station and gravitally movable in the forward direction, means for returning the carrier, and carrier supported blank holding means for engaging and releasing the same respectively at said stations, retarding means consisting of a spring pressed roller 20 and a coacting cam surface to cushion the approach of the carrier to the delivery station, said cam surface having a roller receiving seat for holding the carrier in position at the delivery station.

25. 12. An apparatus for transferring blanks from a receiving station to a delivery station, where the blanks are presented progressively and successively at the receiving station, having a carrier provided with successively actuatable clamps for respectively 30 engaging the blanks, blank actuatable trips for respectively closing the clamps, clamp releasing means at the delivery station, carrier actuating means exerting a constant forward impulse when the carrier is at the receiving station, and carrier holding latches at said receiving station releasable successively by the operation of said trips for permitting step by step forward movements of the carrier.

35. 13. An apparatus for transferring blanks from a receiving station to a delivery station, where the blanks are presented progressively and successively at the receiving station, having a carrier provided with successively actuatable clamps for respectively 40 engaging the blanks, blank actuatable trips for respectively closing the clamps, clamp releasing means at the delivery station, carrier actuating means exerting a constant

forward impulse when the carrier is at the receiving station, and carrier holding latches at said receiving station releasable successively by the operation of said trips for permitting step by step forward movements of the carrier, the path of the carrier as it leaves its initial position at the receiving station being disposed obliquely to the blank supporting plane of said station.

45. 14. A blank transfer apparatus having a carrier exposed when at the loading station to a constant forwardly impelling force and restrained by a holding latch, a pre-set blank engaging clamp on the carrier, a blank actuatable trip for releasing the clamp and means actuatable upon clamp releasing movement of the trip for disengaging said latch.

50. 15. A blank transfer apparatus having a carrier exposed when at the loading station to a constant forwardly impelling force and restrained by a holding latch, a plurality of pre-set successively operable clamps for engaging the blanks or objects, a blank actuatable trip for holding each clamp in its set position, and means actuatable upon clamp releasing movement of one of said trips for disengaging said latch.

55. 16. A blank transfer apparatus having a carrier exposed when at the loading station to a constant forwardly impelling force and restrained by a holding latch, a plurality of pre-set successively operable clamps for engaging the blanks or objects, a blank actuatable trip for holding each clamp in its set position, and means actuatable upon clamp releasing movement of the last of said trips for disengaging said latch.

60. 17. A blank transfer apparatus having a carrier exposed when at the loading station to a constant forwardly impelling force and restrained by a plurality of latches successively operative at short intervals in the advance movement of the carrier, a plurality of pre-set successively operative clamps, blank actuatable trip for holding each clamp in its set position, and means actuatable upon clamp releasing movement of each of said trips for disengaging one of said carrier holding latches.

65. 18. An apparatus for transferring blanks and the like having a carrier movable toward and from a loading station and exposed when at the station to a constant forwardly impelling force, said carrier being provided with blank engaging means, means for holding the carrier at the station, and a blank actuatable trip for controlling the blank engaging means and releasing the carrier.

70. 19. An apparatus for transferring blanks and the like having a carrier movable toward and from a loading station and exposed when at the station to a constant forwardly impelling force, said carrier being provided with blank engaging means, means

for holding the carrier at the station, and blank actuatable trips for respectively controlling the blank engaging means, the carrier holding means being releasable by one of said trips.

20. An apparatus for transferring blanks and the like having a carrier movable toward and from a loading station and exposed when at the station to a constant forwardly impelling force, said carrier being provided with blank engaging means, means for holding the carrier at the station, and blank actuatable trips for successively controlling the blank engaging means, the carrier holding means being releasable by the last actuated trip.

21. An apparatus for transferring blanks and the like having a carrier movable toward and from a loading station and exposed when at the station to a constant forwardly impelling force, the carrier being provided with blank engaging means, means including a plurality of latches for holding the carrier at the station, and blank actuatable trips for respectively controlling the blank engaging means and respectively disengaging said latches.

22. An apparatus for transferring blanks and the like having a carrier movable toward and from a loading station and exposed when at the station to a constant forwardly impelling force, the carrier being provided with blank engaging means, means including a plurality of latches for holding the carrier at the station, and blank actuatable trips for successively controlling the blank engaging means and respectively disengaging said latches.

23. An apparatus for transferring blanks and the like having a carrier movable toward and from a loading station and exposed when at the station to a constant forwardly impelling force, the carrier being provided with blank engaging means, means including a plurality of latches for holding the carrier at the station, and blank actuatable trips for respectively controlling the blank engaging means and successively disengaging said latches.

24. An apparatus for transferring blanks and the like having the carrier movable toward and from a loading station and exposed when at the station to a constant forwardly impelling force, the carrier being provided with blank engaging means, carrier holding means consisting of latches for successively and selectively checking forward movement of the carrier within the load receiving zone of the station, and blank actuatable trips for successively controlling the blank engaging means and consecutively disengaging said latches to permit step by step movements of the carrier.

25. An apparatus for transferring blanks

and the like from a receiving or loading station provided with a progressively movable blank conveying surface, having a carrier provided with blank engaging means, a blank actuatable trip for controlling the blank engaging means, and means actuatable upon the engagement of a blank for raising the same from the conveying surface.

26. An apparatus for transferring blanks and the like from a receiving or loading station provided with a progressively movable blank conveying surface, having a carrier provided with blank engaging means and a blank actuatable trip for controlling the blank engaging means and the release of the carrier, the path of the carrier at the loading station receding abruptly from the plane of said blank conveying surface.

27. An apparatus for transferring blanks and the like from a receiving or loading station provided with a progressively movable blank conveying surface, having a carrier provided with successively operable blank engaging means, successively operative means for holding the carrier at the station and adapted as they are successively actuated to permit limited forward movements of the carrier, and blank actuatable trips for respectively controlling the blank engaging means and successively actuating said carrier holding means, the path of the carrier at the loading station receding abruptly from the plane of said blank conveying surface.

28. A transfer apparatus for blanks having a carrier mounted for forward and return movements between receiving and delivery stations and gravitally movable from a state of rest at the receiving station, means for effecting the return movement of the carrier, means for holding the carrier at the receiving station during the loading operation, blank engaging clamps having members pendent from the carrier and movable to bear against opposite sides of an interposed blank, blank actuatable means for controlling the blank engaging movement of the clamps and releasing the carrier, and means at the delivery station for effecting blank releasing movement of the clamps.

29. A transfer apparatus for blanks having a carrier mounted for forward and return movements between receiving and delivery stations and gravitally movable from a state of rest at the receiving station, means for effecting the return movements of the carrier, means for holding the carrier at the receiving station during the loading operation, blank engaging clamps having members pendent from the carrier and movable to bear against opposite sides of an interposed blank, blank actuatable means for controlling the blank engaging movement of the clamps and releasing the carrier, and means at the delivery station for effecting

blank releasing movement of the clamps, one member of each clamp being mounted for retraction from the plane of blanks at the receiving station to pass thereover during the return movement of the carrier.

30. A transfer apparatus for blanks having a carrier mounted for forward and return movements between receiving and delivery stations and gravitally movable from a state of rest at the receiving station, means for effecting the return movement of the carrier, means for holding the carrier at the receiving station during the loading operation, blank engaging clamps having members pendent from the carrier and movable to bear against opposite sides of an interposed blank, blank actuatable means for controlling the blank engaging movement of the clamps and releasing the carrier, and means at the delivery station for effecting blank releasing movement of the clamps, one member of each clamp being hinged for movement to a folded position during the return movement of the carrier.
31. A transfer apparatus for blanks having a carrier mounted for forward and return movements between receiving and delivery stations and gravitally movable from a state of rest at the receiving station, means for effecting the return movement of the carrier, means for holding the carrier at the receiving station during the loading operation, blank engaging clamps having members pendent from the carrier and movable to bear against opposite sides of an interposed blank, blank actuatable means for controlling the blank engaging movement of the clamps and releasing the carrier, and means at the delivery station for effecting blank releasing movement of the clamps, one member of each clamp being spring retracted to avoid contact with a blank during return movement of the carrier, a cam for restoring said member at the receiving station, means for holding said member in its operative position, and a trip at the delivery station for releasing said member.

32. A transfer apparatus for blanks having a carrier mounted for forward and return movements between receiving and delivery stations and gravitally movable from a state of rest at the receiving station, means for effecting the return movement of the carrier, means for holding the carrier at the receiving station during the loading operation, blank engaging clamps having members pendent from the carrier and movable to bear against opposite sides of an interposed blank, blank actuatable means for controlling the blank engaging movement of the clamps and releasing the carrier, and means at the delivery station for effecting blank releasing movement of the clamps, one member of each clamp being spring retracted to avoid contact with a blank during return movement of the carrier, means

for operatively positioning said member at the receiving station, means for holding said member in its operative position, and means at the delivery station for releasing said member to discharge the blank.

33. A transfer apparatus for blanks having a carrier mounted for forward and return movements between receiving and delivery stations and gravitally movable from a state of rest at the receiving station, means for effecting the return movement of the carrier, means for holding the carrier at the receiving station during the loading operation, blank engaging clamps having members pendent from the carrier and movable to bear against opposite sides of an interposed blank, blank actuatable means for controlling the blank engaging movement of the clamps and releasing the carrier, and means at the delivery station for effecting blank releasing movement of the clamps, one member of each clamp being spring retracted to avoid contact with a blank during return movement of the carrier, a cam for restoring said member at the receiving station, means for holding said member in its operative position, and a trip at the delivery station for releasing said member.

34. A transfer apparatus for blanks having a carrier mounted for forward and return movements between receiving and delivery stations and gravitally movable from a state of rest at the receiving station, means for effecting the return movement of the carrier, means for holding the carrier at the receiving station during the loading operation, blank engaging clamps having members pendent from the carrier and movable to bear against opposite sides of an interposed blank, blank actuatable means for controlling the blank engaging movement of the clamps and releasing the carrier, and means at the delivery station for effecting blank releasing movement of the clamps, the blank engaging elements of the clamps being revoluble on a common axis perpendicular to the plane thereof to permit of turning the blanks.

35. A transfer apparatus for blanks having a carrier mounted for forward and return movements between receiving and delivery stations and gravitally movable from a state of rest at the receiving station, means for effecting the return movement of the carrier, means for holding the carrier at the receiving station during the loading operation, blank engaging clamps having members pendent from the carrier and movable to bear against opposite sides of an interposed blank, blank actuatable means for controlling the blank engaging movement of the clamps and releasing the carrier, and means at the delivery station for effecting

blank releasing movement of the clamps, the blank engaging elements of the clamps being revolute on a common axis perpendicular to the plane thereof, and means for 5 rotating the same to turn the blanks.

36. A transfer apparatus for blanks having a carrier mounted for forward and return movements between receiving and delivery stations and gravitally movable from

10 a state of rest at the receiving station, means for effecting the return movement of the carrier, means for holding the carrier at the receiving station during the loading operation, blank engaging clamps having

15 members pendent from the carrier and movable to bear against opposite sides of an interposed blank, blank actuatable means for controlling the blank engaging movement of the clamps and releasing the carrier, and

20 means at the delivery station for effecting blank releasing movement of the clamps, the blank engaging elements of the clamps being revolute on a common axis perpendicular to the plane thereof, and means for pro-

25 gressively rotating the same to turn the blanks during the movement thereof from the receiving to the delivery station.

37. A transfer apparatus for blanks having a carrier mounted for forward and re- 30 turn movements between receiving and delivery stations and gravitally movable from a state of rest at the receiving station, means for effecting the return movement of the carrier, means for holding the carrier at

35 the receiving station during the loading operation, blank engaging clamps having members pendent from the carrier and movable to bear against opposite sides of an interposed blank, blank actuatable means for controlling the blank engaging movement of

40 the clamps and releasing the carrier, and means at the delivery station for effecting blank releasing movement of the clamps, one member of each clamp being yieldingly im-

45 pelled toward the other, and means actuatable during the return movement of the carrier for setting said clamp member in its open position, said clamp member being held in its set position by said blank actuatable means.

38. A transfer apparatus for blanks having a carrier mounted for forward and return movements between receiving and delivery stations and gravitally movable from

55 a state of rest at the receiving station, means for effecting the return movement of the carrier, means for holding the carrier at the receiving station during the loading operation, blank engaging clamps having mem-

60 bers pendent from the carrier and movable to bear against opposite sides of an interposed blank, blank actuatable means for controlling the blank engaging movement of the clamps and releasing the carrier, and

means at the delivery station for effecting 65 blank releasing movement of the clamps, one member of each clamp being slidably mounted and spring impelled toward the other, a setting lever connected with said member, and a lever actuating cam in the 70 path thereof during movement of the carrier, said clamp member being held in its set position by said blank actuatable means.

39. A mechanism for transferring blanks and the like from a receiving station to 75 a delivery station, having a carrier provided with a clamp for successively engaging and releasing a blank, means for effecting alternate closing and opening movements of the clamp, and carrier actuating 80 devices having means for imparting initial and terminal movement at a reduced speed to the carrier.

40. A mechanism for transferring blanks and the like from a receiving station to a 85 delivery station, having a carrier provided with a clamp for successively engaging and releasing a blank, means for effecting alternate closing and opening movements of the clamp, and carrier actuating devices having 90 means for imparting movement at gradually increasing and gradually decreasing speeds respectively to the carrier upon leaving the receiving and approaching the delivery station. 95

41. A mechanism for transferring blanks and the like from a receiving station to a delivery station, having a carrier provided with a clamp for successively engaging and releasing a blank, means for effecting alternate 100 closing and opening movements of the clamp, and carrier actuating devices having means including a pendulous gravitally influenced element for imparting graduated initial and terminal speed of movement to 105 the carrier.

42. A mechanism for transferring blanks and the like from a receiving station to a delivery station, having a carrier provided with a clamp for successively engaging and releasing a blank, means for effecting alternate closing and opening movements of the clamp, and carrier actuating devices having 110 means including a pendulous gravitally influenced element for imparting graduated initial and terminal speed of movement to the carrier, said element being movable through the vertical plane of its axis.

43. A mechanism for transferring blanks and the like from a receiving station to a 120 delivery station, having a carrier provided with a clamp for successively engaging and releasing a blank, means for effecting alternate closing and opening movements of the clamp, and carrier actuating devices having 125 means including pendulous gravitally influenced element for imparting graduated initial and terminal speed of movement to

- the carrier, said pendulous element being supplemented by spring action during the forward movement of the carrier.
44. A mechanism for transferring blanks and the like from a receiving station to a delivery station, having a carrier provided with a clamp for successively engaging and releasing a blank, means for effecting alternating closing and opening movements of the clamp, and carrier actuating devices having means including a pendulous gravitally influenced element for imparting graduated initial and terminal speed of movement to the carrier, movable through the vertical plane of its axis of suspension with a major portion of its path at the receiving station side of said vertical plane.
45. A mechanism for transferring blanks and the like from a receiving station to a delivery station, having a carrier provided with a clamp for successively engaging and releasing a blank, means for effecting alternate closing and opening movements of the clamp, and carrier actuating devices for imparting movement at a graduated speed thereto, said actuating devices including a pendulous gravitally influenced actuator having a path of movement extending through the vertical suspension.
46. A mechanism for transferring blanks and the like from a receiving station to a delivery station, having a carrier provided with a clamp for successively engaging and releasing a blank, means for effecting alternate closing and opening movements of the clamp, and carrier actuating devices for imparting movement at a graduated speed thereto, said actuating devices including a pendulous gravitally influenced actuator having a path of movement extending through the vertical suspension and supplemented by spring action during its movement from the receiving toward the delivery section.
47. A mechanism for transferring blanks and the like from a receiving station to a delivery station, having a carrier provided with a clamp for successively engaging and releasing a blank, means for effecting alternate closing and opening movements of the clamp, and carrier actuating devices for imparting movement at a graduated speed thereto, said actuating devices including a pendulous gravitally influenced actuator having a path of movement extending through the vertical suspension and opposed as the carrier approaches the delivery station by a progressively resistant supplemental retarding means.
48. A mechanism for transferring blanks and the like from a receiving station to a delivery station, having a carrier provided with a clamp for successively engaging and releasing a blank, means for effecting alternate closing and opening movements of the clamp, and carrier actuating devices for imparting movement at a graduated speed thereto, said actuating devices including a pendulous gravitally influenced actuator having a path of movement extending through the vertical suspension and power actuated propelling means for effecting return movement of the carrier.
49. A mechanism for transferring blanks and the like from a receiving station to a delivery station, having a carrier provided with a clamp for successively engaging and releasing a blank, means for effecting alternate closing and opening movements of the clamp, and carrier actuating devices for imparting movement at a graduated speed thereto, said actuating devices including a pendulous gravitally influenced actuator having a path of movement extending through the vertical suspension, in combination with power actuated propelling means for effecting return movement of the carrier, and means actuatable by the blank releasing movement of the clamps for effecting the application of said propelling means.
50. An apparatus for the purpose specified having a reciprocatory carrier provided with blank engaging means and blank controlled means for closing the same, a pendulous oscillatory actuator for moving the carrier between receiving and delivery stations and gravitally movable when the carrier is loaded, locking means releasable by said blank controlled means for holding the carrier at the receiving station, a continuously operated ratchet concentric with the actuator, a dog carried by the actuator and engageable with the ratchet for communicating return movement to the actuator, and means for disengaging the dog at the limit of said return movement, the blank engaging clamps including a member controlled by blank releasing movement for reengaging the dog with said ratchet.

DONALD ELIJAH PLYMPTON.
